LOCK FOR SETS OF DRAWERS IN OFFICE EQUIPMENT OR THE LIKE

George P. Patriquin, 69 Lynde St.,
Gardner, Mass. 01440

Filed Feb. 16, 1971, Ser. No. 115,900

Term of patent 14 years

Int. Cl. D8—07

U.S. Cl. D8—120

Fig. 1.

Fig. 2.

Fig. 3.

Fig. 4.

Fig. 5.

FIG. 1 is a top plan view of a lock for sets of drawers in office equipment or the like showing my new design;
FIG. 2 is a side elevational view thereof;
FIG. 3 is a bottom view thereof;
FIG. 4 is a front elevational view thereof; and
FIG. 5 is a rear elevational view thereof.
I claim:

The ornamental design for a lock for sets of drawers in office equipment or the like, substantially as shown.
